WARPING-MACHINE.

1,387,893.

Specification of Letters Patent. Patented Aug. 16, 1921.

Application filed November 15, 1918. Serial No. 262,665.

To all whom it may concern:

Be it known that I, GEORGE W. KUENNETH, a citizen of the United States, residing at Paterson, in the county of Passaic and

5 State of New Jersey, have invented certain new and useful Improvements in Warping-Machines, of which the following is a specification.

This invention relates to warping machines and it consists in improvements designed to produce a better quality of product, promote accuracy in the various calculations which the attendant is required to make and facilitate the entire warping operation. One part of my invention consists in novel means for obtaining relative movement as between the reeds and warp in the direction of the length of the reed dents, whereby to prevent the warp threads wearing nicks in the reed dents. Another part of my invention consists in mounting the condensing reed so that it may occupy either of two positions, one the working position and in proximity to the roller or equivalent 15 guide over which the warp extends immediately before being wound on the reel and the other a retracted position to allow free access to the warp at the point where it is just about to be wound on the reed. Another 20 part of my invention consists in novel means for obtaining traverse of the reed carriage when the machine is used for section warping, and also for resetting the carriage manually to each position for laying on the reel 25 a new section of warp. Another part of my invention consists in novel means whereby indication may be afforded as to when the end of a predetermined length of the warp has been wound on the reel, when lease cords 30 should be introduced into the warp and (in section warping) how far back the reed carriage should move to dispose the same accurately in position to start the winding on of a new section of warp. My invention contains certain other novel features of more or 35 less importance to be pointed out herein-after.

In the accompanying drawings,

Figure 1 is a side elevation of my invention, showing the same in place on a warping machine, only parts of the frame and the reel of which are shown;

Fig. 2 is a fragmentary plan of what is shown in Fig. 1, the reel being omitted;

55 Fig. 3 is a vertical sectional view taken in

a vertical transverse plane substantially coincident with a pair of guiding stems for the main reed carriage, the main reed being omitted;

Fig. 4 is a vertical sectional view on the line 4-4 in Fig. 2, the main reed being omitted;

Fig. 5 shows the reed carriage and the reed moving means partly in side elevation and partly in section, the two guide rods on which the carriage moves and the feed screw appearing in section;

Fig. 6 is a horizontal sectional view and Figs. 7 and 8 vertical sectional views on the lines 6-6, 7-7 and 8-8, respectively, of Fig. 5;

Fig. 9 shows in end and side elevation the nut which engages the feed screw;

Fig. 10 shows in end elevation and longitudinal section the worm whereby from the feed screw, also shown in section, the movement of the reeds is obtained;

Figs. 11 and 12 are side and front elevations, the latter partly in section, of the indicator, Fig. 12 also showing in section a clutch between the feed screw and its driver;

Fig. 13 is a plan of the indicator dial and accessories, a part of its driving means appearing in section;

Fig. 14 is a vertical sectional view of what is shown in Fig. 13 taken substantially centrally of the dial; and

Fig. 14^a is a sectional detail of the arm or pointer 39.

a is the frame and *b* the reel of a horizontal warper; in the actual construction shown this warper has means for traversing the reed carriage transversely, that is, parallel with the axis of the reel, allowing the warp to be laid on the reel in sections, spirally, making it therefore what is known as a Swiss horizontal warper.

In the frame are arranged the usual fixed parallel guide rods *c* and between them and preferably in the same horizontal plane is journaled the feed-screw *d*.

The feed-screw is driven in the well-known manner from a sprocket-wheel (not shown) on the reel shaft by a chain *e* and a sprocket-wheel *f* which, however, according to my invention is adapted to be revoluble (see Fig. 11) on the feed-screw *d* between two collars *g* but may be made fast thereto when the conical end *h* of a hand-screw *i* in the end of the feed-screw is inwardly advanced,

by turning such hand-screw, and so through the medium of a wedge-piece *j* arranged in a slot *k* in the feed-screw *j* establishes a frictional interlock between the sprocket-wheel *f* and feed-screw. The mechanism last described obviously constitutes a clutch whereby when the reel is in motion the feed-screw will or will not be rotated according as the clutch is established or disestablished.

The body of the carriage (that is, the carriage proper) is a casting in the form of a simple arch *l* formed at one side with a pair of spaced bearings *m* to receive the rear guide-rod *c* and at the other side with an anti-friction roller *n* resting on the forward guide-rod, its two upright portions being connected by spaced webs *o o* (Figs. 5 and 8), said webs being apertured to receive the feed-screw. There is a vertically movable nut *p* having a pair of stems *q q'* guided in the top of the arch of the carriage body and abutting at one side against one web *o* and at the other side against a worm *r* which in turn abuts the other web *o*, said worm, whose function will appear later, being mounted on the feed-screw and slideable thereon but splined therewith by having a feather *t* engaging in a spline *u* in the feed-screw. In the position shown in Fig. 8 the nut engages the feed-screw so that the carriage will move along the guide-rod if the screw be turned; in this position the nut is held by a pin *v* mounted in the superstructure or arm (to be described) of the carriage and engaging in the upper one of two holes of the stem *q'*. By removing the pin the nut may be held elevated, clear of the screw, upon inserting the pin in the lower one of said holes, whereupon the carriage may be pushed by hand along the guideway, *i. e.*, without turning the feed-screw.

The carriage proper has the depending bearing *w* in which is journaled a shaft *x* carrying a worm-wheel *y* meshing with the worm *r* and a disk *z*.

2 designates the aforesaid superstructure or arm of the carriage fixedly secured upon the body portion *l* thereof. This arm is equipped at its rear end with the usual roller 3 over which the warp extends before being wound on the reel; also with an upstanding bracket 4 for the lease rods 5. In its free end it has a pair of vertical guideways 6 in which the downwardly projecting stems 7 of the reed carrier 8 (to which the main reed 9 is suitably clamped) are guided. In upstanding supports 10 on the arm 2 is fulcrumed between its ends a lever 11 the outer end of which takes under and supports the reed carrier 8 and the inner end of which has a link 12 connecting it with an eccentric point on the crank disk *z*. At the inner end of the lever 11 is a pair of

bosses 13 in which may slide the horizontal stems 14 of the carrier 15 for the condensing reed 16, the bosses having a set-screw 17 to bind against one of the stems to hold the reed carrier in any position to which it is horizontally adjusted.

Here I may mention a noteworthy feature of my invention. In winding on the warp it is very desirable to have the condensing reed as close as possible to the reel *b* in order to secure accuracy of placement of the warp on the reel; on the other hand, the warper frequently requires clear access to the warp between the condensing reed and reel. In working position the parts are arranged as shown in Fig. 1, with the condensing reed at its inward limit with respect to the reel; but when the warper needs to have access between the reed and reel he releases the screw 17 and shifts the reed carrier outward in the bosses 13.

In view of the foregoing it will be obvious that so long as the worm *r* is rotated by the feed-screw the lever 11 will through the parts *y, x, z* and 12 be oscillated, causing the reeds to move up and down with reference to the warp whereby the latter is prevented from cutting nicks in the reed dents.

In Swiss or section warping the warp is wound on the reel in sections of predetermined length and equal width each spirally (by traversing the reed carriage) one after another, the winding on of each section being started with the reed carriage reset beyond the point of its starting to traverse for the winding on of the preceding section a distance which is aimed to be (and in perfectly accomplished section warping should be) exactly equal to a section width. That is, if the carriage traverses to the right, it is reset to the left for the winding on of a new section the distance of its traverse plus the section width. It is very desirable that the warper should be signaled, in the first place, when the end of a section being wound is approaching; it is also desirable that he should have means to indicate when in the winding of a section the lease cords are to be introduced into the warp. It is also desirable that when he manually resets the carriage after winding on one section preparatory of the winding on of another he should have means to indicate accurately when the carriage has reached the proper new position—in other words has been reset the distance of its traverse plus the section width. Such means are shown best in Figs. 11 to 14.

18 is a bracket secured to the near side of the frame *a* in Fig. 1 and penetrated by the feed-screw *d*. Beneath the feed-screw and journaled in the bracket is a shaft 19 (Fig. 1) carrying at the inner side of the bracket a gear 20 and a sprocket-wheel 21 and at the

outer side pinion 22, the gear, sprocket-wheel and pinion being all pinned or otherwise fixed to the shaft. A sprocket-chain 23 extends around the sprocket-wheel 21 and a sprocket-wheel 21' on the feed-screw. Meshing with the pinion 22 and journaled in the bracket 18 is a gear 24 having a handle 25 whereby it may be manually rotated, as in resetting the carriage, having first disestablished the clutch between the feed-screw and sprocket-wheel *f*. Bracket 18 has an arm 26 set at a suitable incline so that a dial 27 which is journaled thereon on a stud 28 (being insulated from the stud by insulation 28', Fig. 14) will be in convenient position for reading. This dial has a scale, as seen in Fig. 13, provided at regular points with indices 0, 1, 2, 3, etc., the intervals between which I find it convenient to mark off into sixteen equal subdivisions; at regular intervals corresponding with these subdivisions I provide holes 29 in the dial to receive metal pegs 30. The dial has peripheral worm teeth 31 meshing with a worm 32 journaled on but insulated (by insulation 33) from a stud 34, the worm being formed on a sleeve 35 equipped with the pinion 36 which meshes with the gear 20. Secured to the arm 26 and insulated therefrom is a spring contact 37 bearing against the under side of the dial, which is of metal. Pivoted in a bracket 38 adjustable radially of the dial is a contact arm 39 overhanging the dial and as to its overhanging portion being beveled on the under side to an edge 40 (Fig. 14^a). This contact arm has a non-conducting pivot 41 and is insulated from the bracket 38 by the non-conducting washers 42. When in the full line position in Fig. 14 it bears against an insulating pad 43. The contact arm 39 and contact piece 37 are the terminals of an electric circuit 44 including a battery 45 and an alarm device 46. I find it convenient to provide in the contact arm two holes 47, 48 in the latter of which a pin 49 is placed when not in use and the former of which is employed as herein-after stated.

The warper places in the holes 29 of the dial a peg 30 (as the one opposite the numeral 3) which is to serve to indicate that a predetermined number of yards for the section to be wound has been wound on the reel; at suitable intervals between this peg and 0 on the dial he places other pegs 30 in the holes, which are to serve to indicate when the lease cords are to be placed in the warp; finally in another hole a suitable distance from 0 and reading backward on the dial he places another peg, as the one near the numeral 11. It is assumed, of course, that when the winding on of a section is thus being prepared for, the dial (which may be removed from its bearing and replaced) is arranged with 0 opposite the pointer which the contact arm 39 affords. When the winding on of the section ensues, the clutch between the sprocket-wheel *f* and feed-screw *d* being established and the carriage being therefore traversed through the medium of the feed-screw and nut *p*, the feed-screw through 21', 23, 21, 36, 35, and 32, drives the dial, which by reference to the pointer 39 indicates by the numbers 1, 2, 3 etc. and the subdivisions the amount of yardage wound on. As the dial rotates the pegs 30 successively engage the arm 39 and close the electric circuit to actuate the alarm 46, so that the operator is advised to stop the machine either to insert a lease cord or to sever the warp at the end of the section length predetermined, according as it is any one but the last or the last peg which thus closes the circuit. When the last peg closes the circuit and the machine is stopped and the predetermined length of warp is cut off and properly secured to the reel the attendant disestablishes the clutch and then turns the handle 25 in a direction to reverse the rotation of the feed-screw and the dial. This results in feeding the carriage reversely to the direction in which it was automatically fed under the influence of the reel. The reversing operation is carried on not simply until 0 on the dial reaches the pointer (which means that the carriage is back to its previous starting point of traverse) but until the peg near the index 11 contacts with the pointer, whereupon the alarm will again be sounded, this time indicating the position of the carriage for starting its traverse in the winding on of the next section. At this point it may be remarked that it is very essential, in order that the starting position of the carriage for the winding on of a new section shall be accurately determined, that the last-named peg be brought by the manual shifting of the carriage to its new position directly opposite the arm 39, for which purpose the pin 49 may be removed from the hole 48 and inserted in the hole 47 and in the space between the two teeth which are directly opposite the peg; some such expedient as this is necessary, else there might be a spacing between the section already wound on and the one next to be wound on which is greater than the distance between the threads in the warp, so that in the finished warp (composed of all the sections finally wound on the reel) there would result an undue space or break. The carriage being now positioned ready for the laying on of the new section of warp, the arm 39 is swung to the dotted line position in Fig. 14, the dial removed and replaced with 0 opposite the pointer and with its teeth in mesh with the worm 32, whereupon the pointer is returned to its full line position. Having established the clutch between *f* and *d* the winding on of a new section is ready to begin.

"Clocks" or indicators heretofore devised for warping machines have, so far as I am aware, been invariably operated from the shaft of the reel, whereby only the yardage wound on the reel may be determined. According to my invention, since the dial is in effect geared with the reed carriage, obtaining its motion from the intermediary part of the gearing which the feed-screw affords, it is possible not only to determine the extent of yardage wound on the reel but the extent of traverse of the carriage, and of the resetting traverse motion thereof, moreover, as well as of the working traverse motion thereof.

Having thus fully described my invention, what I claim as new and desire to secure by Letters Patent is:—

1. In combination, a supporting structure, a reel journaled therein, a reed carriage arranged to traverse in said structure, indicating means including a movable indicating member, a rotary train operatively

connecting said carriage and member and adapted to traverse the former and move 25 the latter in synchrony with each other, and means to transmit motion from the reel to said train having a disconnective clutch connection.

2. In combination, with the frame, a reel 30 journaled therein, a reed carriage arranged to traverse in the frame, a rotary feed-screw operatively engaged with and adapted to traverse the carriage, means to transmit motion from the reel to the feed-screw having a disconnective clutch connection, means to manually rotate the feed-screw, means to indicate the length of warp wound on the reel and the extent of traverse of the carriage including a moving member, and 40 means, connecting said member with the feed-screw, to move said member in synchrony with the rotating feed-screw and traversing carriage.

In testimony whereof I affix my signature. 45
GEO. W. KUENNETH.
